J. SYLVAN

GLAZING BAR FOR SKYLIGHTS AND THE LIKE

Filed June 16, 1921

UNITED STATES PATENT OFFICE.

JOSEPH SYLVAN, OF CHICAGO, ILLINOIS.

GLAZING BAR FOR SKYLIGHTS AND THE LIKE.

Application filed June 16, 1921. Serial No. 477,886.

To all whom it may concern:

Be it known that I, JOSEPH SYLVAN, a citizen of the United States, and a resident of Chicago, in the county of Cook and State 5 of Illinois, have invented certain new and useful Improvements in Glazing Bars for Skylights and the like; and I do hereby declare that the following is a full, clear, and exact description thereof, reference being 10 had to the accompanying drawings, and to the letters of reference marked thereon, which form a part of this specification.

This invention relates to improvements in "glazing bars" for skylights and the like and 15 consists of the matters hereinafter described and more particularly pointed out in the appended claims.

One of the objects of the invention is to provide a simple and efficient glazing bar 20 which may be made from sheet metal and which so grips or clamps the marginal parts of the glass panels of the skylight as to form a watertight seal between the glazing bar and panel without the use of putty 25 or like material.

Other objects of the invention as well as the several advantages thereof will more fully appear as I proceed with my specification.

30 In the drawings:—

Fig. 1 illustrates a partial transverse vertical sectional view through a skylight construction embodying my improved glazing bar.

35 Fig. 2 is a transverse vertical section on an enlarged scale, through a glazing bar and the marginal parts of adjacent glass panels, the plane of the section being indicated by the line 2—2 of Fig. 1.

40 Fig. 3 is a detail view illustrating the manner of introducing the margin of a glass panel into one of the glazing bar strips.

Fig. 4 is a perspective view of a fragment of glazing bar strip made in accordance with my invention.

45 Fig. 5 is a detail perspective view of one end of a cap strip associated with my improved glazing bar.

In general my improved glazing bar includes a channel or V-shaped sheet metal strip, the top part of one of the side members of the strip being bent to overhang but being spaced from the top edge of the other side member to provide a laterally opening 50 slot near the top of the strip. This slot re-

ceives one margin of a glass panel and when the strip rests with its bottom edge upon the stringers of a skylight and a panel is entered into the slot, the weight of the panel will cause the strip to rock or tilt laterally 60 toward the panel about its bottom edge. When the strip is thus rocked, its top parts which define the slot, engage and securely clamp the top and bottom surfaces of the 65 marginal part of the panel.

Referring now in detail to that embodiment of the invention illustrated in the accompanying drawing, 10 indicates a truss forming a part of a skylight structure which truss includes a horizontal bottom bar 11, an upright middle bar 12 and oppositely inclined roof rafters 13 which are fixed at their ends to the ends of the bottom bar and to the top end of the upright middle bar 12. Brace bars 13^a are provided to connect the 70 middle parts of the roof rafters with the middle part of the horizontal bar which rests at its ends upon and is fixed to the usual curb walls 14 (only one of which is shown in Fig. 1) defining the sides of the 75 skylight opening.

Connecting the trusses together are longitudinal top or inner stringers 15, bottom or outer stringers 16 and intermediate stringers 17, all preferably made of angle bars. Secured to the bottom and intermediate stringers 16 and 17 are combination or eaves gutter strips 18 and 19 respectively and engaging both top stringers 15 is a one-piece ridge strip 20, said strips all being made of sheet 80 metal bent into suitable form.

The combination or eaves gutter strip 18 includes a hooked flange 18^a which engages the stringer 16 as shown, and two upright webs 18^b—18^c respectively spaced from each other and forming stop shoulders for the outer ends of the bottom glazing bars 21 and bottom panels 22. In the web 18^b is a plurality of holes 18^d. The web 18^c terminates in a vertically depending hook flange 18^e 95 and said flange together with the web 18^c receives and holds a deflector plate 23 which prevents the wind from blowing in through the openings 18^d.

The eaves gutter strip 19 includes a 100 hooked flange 19^a which engages the intermediate stringer 17 as shown, and two upright webs 19^b—19^c respectively which are spaced from each other and form stop shoulders for the outer ends of the top glaz- 110

ing bars 24 and top panels 25. In the web 19^b is a plurality of holes 19^d. The web 19^c terminates in a vertical depending hook flange 19^e and said flange together with the 5 web 19^c receives and holds a deflector plate 26 which prevents the wind from blowing in through the openings 19^d. Between the hook flange 19^a and the web 19^b, the strip is formed to provide an outwardly opening 10 groove 27 the purpose of which will presently appear.

The ridge piece 20 has oppositely inclined 15 side members 20^a which are folded upon themselves to form outwardly opening grooves 20^b and hook flanges 20^c which engage the top stringers 15.

The glazing bars 21—24 being identical in 20 form and construction, a detailed description of one will suffice for both. Each bar is made up of a pair of substantially channeled or V-shaped sheet metal strips 28—28 and each strip comprises inner and outer 25 side walls or members 29 and 30 which are connected together along their bottom edges and diverge upwardly and outwardly therefrom. The inner side member 29 is of a height greater than the outer side member 30 and its top marginal part is bent at substantially a right angle to form a web 31 30 which overhangs but is spaced from the top edge of the member 30 to provide a laterally opening slot 32 of a width greater than the thickness of the panel used in connection therewith. The web 31 terminates 35 in an upturned flange 33.

The panels 22—25 are glass panels and 40 are preferably of the kind having the ribs 34 on the underside arranged parallel with the glazing bars. The glazing bars 21—24 are shorter in length than their associated panels; the glazing bars 21 engaging at their 45 ends against the shoulders 18^b and stringers 17 and the glazing bars 24 engaging at their ends against the shoulders 19^b and stringers 15 respectively.

To assemble the panels and glazing strips 50 said strips are placed in pairs upon the skylight framing and are spaced apart a distance substantially equal to the width of the panels. One strip of each pair is then made to assume a substantially upright position as shown in Fig. 3 when the margin of a panel is introduced into the slot 32. When 55 this has been done, the top edge of the outer side member of the strip will engage in one of the grooves between adjacent ribs 34 on the underside of the panel when the weight of the panel will cause the strip to tilt or rock laterally about its bottom edge until the outer edge of the web 31 engages the top 60 surface of the panel as shown in dotted lines in Fig. 3. When the panels 21—24 are in place the top end parts of the top panel will extend into the side grooves 20^b of the 65 ridge strip and the top end parts of the

bottom panels will extend into the grooves 27 in the sides of the combination or eaves strips 19.

Associated with each pair of glazing strips is a cap strip 35 which includes a horizontal web 36, and depending side flanges 37, the outer end of the web being formed to provide a bendable tail piece 38. To apply the cap strip in place, the flanges 33 of both glazing strips are sprung inwardly toward each other to permit the flanges 37 of the cap strip to pass, after which the flanges of the glazing strips engage the flanges of the cap strip to hold them in place upon the glazing bars. The top ends of the cap strips 80 extend into the grooves of the ridge strip 20 and the combination or eaves strips 19 respectively while the tail or outer ends 38 of the cap strips are bent about the flanges 18^c—19^c of the eaves strips to secure the outer 85 ends of the cap strips in place. Thus the cap strips prevent any rain, snow or dust from passing in between the glazing strips, and the side flanges of the cap strips act to prevent any rain from blowing or seeping in 90 between the glazing strips and panels. The ends of the bottom part of the glazing strips are cut away as shown in Figs. 1 and 4 so that such water of condensation as drips from the margins of the panels and falls in 95 between the side members of the strips, is discharged from the lower outer ends thereof and passes through the openings 18^d—19^d of the eaves strips to be discharged upon the outside of the skylight. The webs 31 and 100 flanges 33 of the strips also provide gutters which discharge at the lower ends of the strip, such water as they may catch.

The improved glazing bar provides a 105 water tight seal or connection at the adjacent margins of the panels without the aid of putty or like material. They are made of sheet metal and therefore they decrease the weight which the skylight structure must sustain, and may be made at a less cost than the rolled glazing bars now in use. No extraneous fastening means, such as bolts and rivets, are used in the assembly, consequently a saving in labor is effected. Should any 110 one of the panels become broken, it may easily be removed and replaced by a new one.

While in describing my invention, I have referred to certain details of construction and arrangement of parts, I do not wish to 115 be limited thereto except as may be pointed out in the appended claims.

I claim as my invention:—

1. A glazing bar comprising a channel-like member having side wall parts arranged to 125 define a longitudinally extending slot along one side of said channel like member, adapted to receive the marginal part of a skylight panel, said member being capable of a lateral rocking movement about its bottom edge 130

- from an upright to an inclined position under the weight of the panel to cause the parts thereof defining the slot to clamp upon the marginal part of the panel. 45
5. 2. A glazing bar comprising two channel-like members, each having side wall parts arranged to define longitudinally extending slots along opposite sides of said channel like members, adapted to receive the marginal parts of adjacent panels of a skylight, said 50 members being capable of a lateral rocking movement away from each other about their bottom edges from an upright to an inclined position under the weight of the panels to cause the parts defining the slots to clamp upon said marginal parts thereof of the panels. 55
6. 3. The combination with a glazing bar comprising two channel-like members, each having side wall parts arranged to define longitudinally extending slots along opposite sides of said channel like members, adapted to receive the marginal parts of adjacent panels of a skylight, said members being capable of a lateral rocking movement away from each other about their bottom edges from an upright to an inclined position under the weight of the panels to cause the parts thereof defining the slots to clamp upon said marginal parts of the panels, and a cap strip engaging the top parts of both of said members and covering the space therebetween. 60
7. 4. In combination with a glazing bar comprising two channel-like members, each having side wall parts of different heights, the higher side wall part of one channel like member having a top web which overhangs and is spaced from the top edge of the other side wall part to define longitudinally extending slots along opposite sides of said channel like members, each web terminating in an upturned flange, the said slots being adapted to receive the marginal parts of 65
8. adjacent panels of a skylight, both of said channel like members being capable of a lateral rocking movement away from each other about their bottom edges under the weight of the panels to cause the parts thereof defining the slots to clamp upon the said marginal parts of the panels, and a cap strip having a web and depending side flanges, the web of the cap strip covering the space between said members and the flanges of the cap strip engaging the upturned flanges of the webs of both channel members. 70
9. 5. A glazing bar strip comprising two side wall parts of different heights which diverge outwardly from each other from their bottom margins, the marginal top part of the side wall part of greater height being bent to overhang but being spaced from the edge of the side wall part of lesser height to provide a longitudinally extending slot along one side of the glazing bar strip adapted to receive the marginal part of a skylight panel. 75
10. 6. A glazing bar strip comprising two side wall parts which diverge outwardly from each other from their bottom margins, the marginal top part of said wall part of greater height being bent at substantially a right angle to form a web which overhangs but is spaced from the edge of the said side wall part of lesser height to provide a longitudinally extending slot along one side of the glazing bar strip adapted to receive the marginal part of a skylight panel, said web terminating in an upturned flange which is arranged in substantially the plane of one of said side wall parts of the glazing strip. 80

In testimony that I claim the foregoing as my invention, I affix my signature in the presence of two witnesses, this 3rd day of June, A. D. 1921.

JOSEPH SYLVAN.
